[57] CLAIM

The ornamental design for a reflective unit for trailers
or the like, as shown and described.

DESCRIPTION

FIG. 1 is a front elevational view of a reflector unit for
trailers or the like showing our new design;

FIG. 2 is a right side elevational view thereof, with the
opposite side being a mirror image;

FIG. 3 is a bottom plan view thereof;

FIG. 4 is a top plan view thereof; and,

FIG. 5 is a rear elevational view thereof.

FIG. 1

FIG. 2

FIG. 3

FIG. 4

FIG. 5
